HARVEY LEE MOORE, OF PITTSBURGH, PENNSYLVANIA, ASSIGNOR OF ONE-HALF TO
WILLIAM C. STRIPE, OF PITTSBURGH, PENNSYLVANIA.

STOKING MECHANISM.

1,267,439.

Specification of Letters Patent. Patented May 28, 1918.

Application filed June 19, 1916. Serial No. 104,628.

To all whom it may concern:

Be it known that I, HARVEY LEE MOORE, residing at Pittsburgh, in the county of Allegheny and State of Pennsylvania, a citizen 5 of the United States, have invented or discovered certain new and useful Improvements in Stoking Mechanism, of which improvement the following is a specification.

In the type of stoker employing a plunger 10 for forcing the coal into the fire chamber, it is undesirable that the plunger should fit so closely in the shell in which it reciprocates, as to prevent the entrance of dust between the plunger and shell. As the plunger reciprocates, considerable quantities of dust 15 are worked back to the rear of the plunger, and either drop into the fire room or if the rear or the outer end of the shell is closed, will soon accumulate in sufficient amount to 20 prevent the operation of the plunger.

The invention described herein has for its object the provision of means for preventing wholly or to a large extent the movement 25 of dust to the rear of the plunger. The invention is hereinafter more fully described and claimed.

In the accompanying drawings, forming a 30 part of this specification Figure 1 is a sectional elevation of a portion of a stoking mechanism embodying my improvement, Fig. 2 is an elevation of a plunger constructed in accordance with my invention; Fig. 3 is a sectional view on a plane indicated by the lines 3—3 Fig. 2, and Fig. 4 is a view similar to 35 Fig. 2 illustrating a modification of the improvement.

In the practice of the invention the plunger 1 is reciprocated by any suitable means, transverse to the lower end of the hopper 2 40 to force the coal into the opening 3 leading to the fire chamber. When in operative position the plunger rests within a shell 4, which serves as a guide for the plunger, when reciprocated. It is undesirable for several 45 reasons to construct the plunger so as to fit closely in this shell, and hence fine dust will pass in between the shell and plunger. The reciprocation of the plunger will move the dust back and forth, but as the fuel in front 50 of the plunger will prevent to some extent the movement of the dust forward toward the fire-box, the larger per cent. will be worked to the rear of the plunger or to the left in Figs. 1 and 2 and finally drop into 55 the fire room; if the rear end is closed the

accumulated dust will prevent the operation of the plunger.

In order to insure the movement of all or the major part of the dust toward the firebox, the plunger is provided with one or 60 more grooves 5, which may extend entirely around the plunger as shown in Fig. 4, or may extend about one-half around a portion of the periphery on the under side of the plunger, as shown in Figs. 1, 2 and 3. These 65 grooves are made with the rear wall *a* at an angle, preferably a right angle, to the axis of the plunger, while the front wall *b* is made so as to be inclined forward in the direction of movement. When the plunger is 70 reciprocated forwardly or to the right, the abrupt shoulder *a* will tend to force the dust contained therein toward the fire box, but when the plunger is moved to the rear 75 or open end of the shell or cylinder the inclined wall *b*, bearing on the dust will tend to raise the plunger permitting it to over ride the dust and the crowding of the dust from the grooves into the sphere between the plunger and shell. It will be found that by 80 this construction, very little dust will be worked to the rear of the plunger and hence the fire-room will be practically free from dust.

It will be readily understood by those 85 skilled in the art that as long as the wall *a* of the groove has a greater inclination to the axis of the plunger than the wall *b*, the movement of the plunger will cause a larger percentage of the dust to be moved toward 90 the fire-box. It is preferred that the grooves should be arranged adjacent to the front end of the plunger, so that dust will be excluded from between the main portion of the plunger and shell, and such portion will not be subject to abrasion by the 95 dust.

If desired the grooved portion of the plunger, may be so constructed as shown in Fig. 4 as to provide greater clearance between the 100 under side of the plunger and the shell, as shown in Fig. 4. Such construction will facilitate the movement of dust from the groove or grooves on the rearward movement of the plunger.

I claim herein as my invention:

1. In a stoking mechanism the combination of a hopper, a plunger guiding shell arranged at an angle to the movement of the fuel in the hopper, and a reciprocating plun- 110

ger for forcing fuel into the fire-box and movable back and forth in the shell, said plunger being provided in its underside with a groove having its rear end at a greater inclination than its front, to the axis of the plunger.

2. In a stoking mechanism the combination of a hopper, a plunger guiding shell arranged at an angle to the movement of fuel through the hopper, and a reciprocating plunger for forcing fuel into the fire-box said plunger being provided with a groove in its under side having its rear wall in a plane at an approximately right angle to the axis of the plunger, and its front wall in a plane at an angle less than a right angle to the axis of the plunger.

3. In a stoking mechanism the combination of a hopper, a plunger guiding shell arranged at an angle to the movement of the fuel in the hopper, and a reciprocating plunger for forcing fuel into the fire-box and movable back and forth in the shell, said plunger being provided with a groove having its rear wall at a greater inclination than its front, to the axis of the plunger, a section of the grooved portion of the plunger being formed in the arc of a circle of less diameter than that of other portions of the plunger.

In testimony whereof I have hereunto set my hand.

HARVEY LEE MOORE.
